Primary Examiner — Leanne Was-Englehart*Assistant Examiner* — Jasmine L. Comedy*(74) Attorney, Agent, or Firm* — Tucker Ellis LLP(57) **CLAIM**

The ornamental design for a partition wall, as shown and described.

DESCRIPTION

FIG. 1 is a front, right side and top perspective view of a partition wall showing our new design;

FIG. 2 is a rear, right side and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the partition wall that form no part of the claimed design.

1 Claim, 4 Drawing Sheets(56)
